UNITED STATES PATENT OFFICE.

WILLIAM G. LUTTINGER, OF JEROME, ARIZONA.

BURNER.

1,346,904.

Specification of Letters Patent. Patented July 20, 1920.

Application filed April 23, 1919. Serial No. 292,038.

To all whom it may concern:

Be it known that I, WILLIAM G. LUTTINGER, a citizen of the United States, residing at Jerome, in the county of Yavapai and State of Arizona, have invented certain new and useful Improvements in Burners, of which the following is a specification.

This invention relates to stoves and more particularly to a burner therefor.

10 One of the objects of this invention resides in the provision of a burner which can readily be utilized in connection with any type of stove.

Another object of this invention resides in 15 the provision of a burner for stoves which consists of a certain embodiment of elements that coact in discharging vapor of a highly combustible quality.

A further object of this invention resides 20 in the provision of a burner for stoves which is adapted to vaporize oil and water and cause the same to commingle to form a highly combustible product.

With these and other objects in view, this 25 invention resides in certain novel features of construction and arrangement of elements to be more particularly set forth in the specification herewith and pointed out in the appended claim, it being understood 30 that the right is reserved to resort to such changes in construction as come within the scope of the claim.

In the accompanying drawing:—

Figure 1 is a front view of a portion of 35 kitchen range showing the front wall to the fire-box thereof broken away and the burner comprising this invention in operative position therein;

Fig. 2 is a sectional view on line 2—2 of 40 Fig. 1;

Fig. 3 is an enlarged plan of the burner showing certain portions thereof in section.

In the accompanying drawing the latter A 45 designates an ordinary kitchen range having a fire-box B of the usual form.

Resting in the fire-box B of the aforesaid range is an asbestos pan 5 in which is disposed a metallic drip pan 6 for retaining a certain amount of oil therein to start the 50 generation of steam within the generators 8 which are supported above the drip pan 6. The generators 8 comprise elongated and cylindrical tanks preferably horizontally disposed and arranged in parallelism and 55 one of said generators or tanks serves as a superheater for the steam generated in the

tank into which the water is initially injected or delivered.

The aforesaid steam generators are connected adjacent their central positions by a 60 pipe 10 and directed into the bore of one of the generators is a perforated nozzle 12 that is connected to a water conduit 13 leading from a water reservoir 14. The nozzle 12 extends within the coacting steam generator 65 or tank 8 through an end thereof and the walls of said nozzle within said generator or tank are provided therewith along with minute openings so that substantially a splash system of steam generation will be effected. 70

Leading from the other generator is a conduit 15 which is adapted to conduct the steam that is generated in the generators to a nozzle 16 which is in close proximity to an oil discharging nozzle 17 at the terminal 75 of an oil conduit 18 that is connected to an oil reservoir 20.

The oil and water reservoirs are herein disclosed as being formed by dividing a tank in sections, but since the burner will 80 operate where the oil and water are conveyed from separate tanks, I do not want to be limited to the use of a partition tank.

The conduits 13 and 18 are provided with valves 21 and 22 for regulating the flow 85 therethrough and to also completely close said conduits when it is necessary to extinguish the fire.

The conduits 13 and 18 are provided with unions 23 and 24 so that the burner and 90 reservoirs can be disconnected.

With the aforesaid assemblage of elements the drip pan is filled with oil and ignited, then the water is injected into one of the generators 8 where it is converted into steam 95 and such steam passes through the other generator and conduit 15 to the nozzle 16 which injects the steam into the spray of the lighted oil nozzle 17 and by being so discharged, the oil and vapor will commingle 100 and form a highly combustible product.

As is clearly illustrated in Figs. 1 and 3 of the drawings, it is to be noted that the conduit 15 leads from the end of the second tank 8 corresponding to the end of the 105 first tank through which the nozzle extends. The conduit 15 extends outwardly and laterally with respect to said second tank 8 and is then continued rearwardly in close proximity to and substantially in parallelism 110 with said second tank 8 to a point slightly beyond the opposite end of said tank. The

conduit 15 is then disposed transversely relative to both of the tanks 8 and terminates slightly beyond the first tank and is continued by a portion arranged outwardly of 5 and in close proximity to said first tank 8 substantially in parallelism therewith. This latter portion of the conduit 15 terminates in advance of the forward end of the first named tank 8 or that end through which 10 the nozzle extends and is continued by an inwardly disposed and laterally directed portion which leads to the nozzle 16. The nozzle 16 is positioned between the tanks 8 and extends inwardly thereof, as is clearly 15 illustrated in Fig. 3. As shown in Fig. 3, it is to be noted that the oil discharging nozzle 17 terminates in advance of the nozzle 16 or, in other words, the discharge end of the nozzle 16 is inwardly of the discharge 20 end of the nozzle 17.

It is also to be noted that the portions of the conduit 15 are coplanar or substantially coplanar and also substantially coplanar with the vertical centers of the tanks 8. By 25 this particular arrangement of the conduit 15, it will be at once understood that the steam passing through the conduit 15 to the nozzle 16 is prevented from condensing by the heat radiating from the various parts 30 of the assembled burner, whereby the efficiency of the device is maintained at a relatively high degree.

With this invention fully set forth, it is

manifest that a burner is produced which is cheap of manufacture, readily operable and 35 economical in the consumption of fuel.

Having thus described this invention what I claim is:—

A burner of the class described comprising, in combination, spaced tanks, each of 40 said tanks being closed, a connection between the tops of the tanks whereby one of said tanks discharges into the other, a nozzle leading from a source of water supply and discharging within one of the tanks 45 through an end thereof and extending axially of the tank a material distance therein, the walls of the nozzle within said tank being perforated, a conduit leading from the second tank and terminating in a nozzle positioned between the tanks and extending inwardly thereof and in close proximity thereto, said conduit leading from the end of the second tank corresponding to the end of the first tank through which the nozzle 50 extends, said conduit extending around the tanks, the portions of the conduit, the nozzle and the tanks being substantially coplanar, and an oil nozzle positioned between the tanks and in close proximity to the first 55 named nozzle, the discharge end of the first named nozzle being inwardly of the discharge end of the second named nozzle.

In testimony whereof I affix my signature.

WILLIAM G. LUTTINGER.
